F. TOMLINSON.
DRIVING AND RELEASING MECHANISM.
APPLICATION FILED JAN. 14, 1911.

1,056,071.

Patented Mar. 18, 1913.

FIG. 1.

UNITED STATES PATENT OFFICE.

FENTON TOMLINSON, OF SAN DIEGO, CALIFORNIA, ASSIGNOR OF ONE-HALF TO OLIVER J. WINSTON, OF SAN DIEGO, CALIFORNIA.

DRIVING AND RELEASING MECHANISM.

1,056,071.

Specification of Letters Patent. Patented Mar. 18, 1913.

Application filed January 14, 1911. Serial No. 602,732.

To all whom it may concern:

Be it known that I, FENTON TOMLINSON, citizen of the United States, residing at San Diego, in the county of San Diego and State 5 of California, have invented certain new and useful Improvements in Driving and Releasing Mechanism, of which the following is a specification.

My invention relates to mechanical movements and particularly to means for driving a driven element from a driving element and at will releasing the driven element from the driving element.

The object of the invention is to provide 15 a simple and reliable rotary driving mechanism including means for transferring the driving motion from one element thereof to another element and in connection therewith to provide reliable and quickly operating 20 means for automatically disengaging the driven element from the driving element, either while the two elements are in a state of motion or of rest upon the reversing of the motion of the driving element.

25 A further object is to provide means whereby the forces acting on the driving element to get reverse motion can either be applied directly to the driving element or applied directly to the driven element.

30 My mechanical movement is shown in the accompanying drawings, it being understood that the movement may be applied to a large variety of mechanism.

In the drawings: Figure 1 is an elevation 35 of one embodiment of my invention. Fig. 2 is a like view but partly in section. Fig. 3 is an end view, the shaft being shown in section. Fig. 4 is a like view to Fig. 3 but showing the position of the parts when the 40 driving element is reversed in the direction of its movement. Fig. 5 is a fragmentary section of a crank case with my improvement applied thereto.

45 Corresponding and like parts are referred to in the following description and indicated in all the views of the accompanying drawings by the same reference characters.

It is to be understood that in the above drawings my improved mechanical motion 50 has been shown by itself and not applied to any particular mechanism, though it may be applied to a large variety of apparatus where it is necessary to quickly release the

driven element of said mechanism from a driving element.

55

In the embodiment of my invention which is illustrated in the drawings, 2 designates a central shaft which is supported in any suitable manner and which is surrounded by a tubular rotatable shaft 3 which forms 60 the driving shaft, this rotatable shaft 3 being driven in any suitable manner and being provided with the rotatable driving element 4, which in the illustration of my invention has the form of a disk. It is to be 65 understood that while I have shown the disk 4 as being mounted upon and driven with the tubular shaft 3, the disk 4 might be driven in any suitable manner and rest directly upon the shaft 2. Located immediately adjacent to the disk 4, as for instance upon the shaft 2, is a rotatable driven element 5 which in this embodiment of my invention has the form of a disk, which disk is provided upon its circumference with 70 ratchet teeth 6.

Located immediately adjacent to the disk 5 and in fixed relation to the driving and driven members 4 and 5, is a fixed element 7 also having the form of a disk and shown 80 as mounted upon the shaft 2 but non-rotatable therewith. In the illustration this disk 7 is supported by means of a bracket 8 which extends upward from a base 9 supported in any suitable manner. I do not 85 wish to limit myself, however, to any particular means for supporting the disk 7 fixedly with relation to the driving and driven elements.

In order to convey motion from the driving element 4 to the driven element 5, I mount upon the inner face of the driving element the pawl 10. This is pivoted at its outer end as at 11 adjacent to the circumference of the disk and its free end is angularly bent and adapted to engage with the ratchet teeth 6. A spring 12 may be used to force the free end of the pawl 10 into engagement with the ratchet teeth 6 and a stop 13 may be used to limit the outward 100 movement of the pawl. I do not, however, wish to limit myself to these features.

Pivottally mounted upon the pawl 10 is a pawl 14 which is oppositely directed with relation to the pawl 10 and which engages 105 with relatively short ratchet teeth 15 formed

upon the periphery of the fixed element 7. These ratchet teeth 15 are reversely disposed with relation to the ratchet teeth 6 just as the pawl 14 is reversely disposed relatively to the pawl 10. A spring 16 holds the pawl 14 into engagement with the ratchet teeth 15.

Upon a movement of the driving element 4 in the direction of the arrow A the pawl 10 will engage with the teeth 6 and as a consequence rotate the driven element 5 in the direction of the arrow A and at the same speed as the driving element. Upon a reversal of the driving element 4, however, the pawl 14 will engage against one of the teeth 15 and as a consequence immediately upon a reversal of the driving element the pawl 14 will act to lift the pawl 10 out of engagement with the teeth 6, as illustrated in Fig. 4, thereby entirely releasing the driven element from engagement with the driving element. As soon, however, as the driving element is again reversed so that its movement is in the direction of the arrow A in Fig. 1, the pawl 16 will rock upon its fulcrum against the teeth 15 and permit the pawl 10 to again engage the teeth 6 of the driven element.

While I have shown the release as actuated by a reverse movement of the driving element and have referred to the element 7 as being relatively fixed, it is to be understood that the element 7 may be shiftable, in which case the element 7 when moved quickly in the direction of the arrow A in Fig. 1 would operate to force the pawl 10 out of its engagement with the ratchet teeth 6. It will be seen that the rearward movement of the element 4 is very slight in order to cause a disengagement of the parts and that the disengagement is direct. Furthermore, that the release is positively effected and that it is immediate.

While I may mount the fixed element 7 in any suitable manner, I have shown the fixed element as being mounted upon a standard 9 or base which forms a journal for the shaft 2. The bracket 8 I have shown as angular in form and provided with a slot 17, while mounted upon the upper face of the standard or base 9 is a bracket 8^a which is also slotted as at 17. Pins project from the fixed element 7 and extend into these slots, the pins being provided with nuts whereby the fixed element may be adjusted toward or from the element 5. This adjustability is particularly necessary in case there is a clutch connection or arrangement on the crank shaft 2.

While I do not wish to limit myself to any particular application of my invention, I will describe its application to the cranking device of an internal combustion engine. In this application of my invention the construction I have devised acts as a safety device to prevent the back kick of the crank.

If the shaft 2 is connected with the crank shaft of the engine on one end, as indicated in Fig. 1, and provided with a crank and handle on its opposite end, the operator by actuating the crank in one direction will cause the crank shaft to revolve. This cranking operation is required to start up most internal combustion engines and the operation is very dangerous. Quite often an engine will back fire when being cranked. This back firing throws the crank back with a sudden, powerful force without any warning and often results in serious injury to the operator. By using my invention, the danger is done away with, in that when the shaft 2 reverses under a back fire the shaft travels only an extremely small distance before effecting the disengagement of the shaft 2 and the driving member 3.

In Fig. 5 I show the application of my invention to a crank case. In this figure 19 designates the crank case, 20 the crank shaft, 21 the pawl mounted upon the crank case or driving member and engaging with a ratchet upon the driven member. 22 designates the pawl which is pivotally mounted upon the first named pawl and which engages with the relatively fixed ratchet 25. 24 designates the ratchet wheel formed with or mounted upon the crank shaft. The pawls 21 and 22 are equivalent to the pawls 10 and 14 previously described, and the ratchet wheels 24 and 25 are equivalent to the ratchet wheels 5 and 7 heretofore described. The pawl 21 is forced into engagement with the ratchet teeth on wheel 24 by means of a spring 26, while the pawl 22 is forced into engagement with the ratchet teeth on wheel 25 by means of a spring 27. The only difference between this construction and that previously described is the fact that the pawl 22 is rotatably mounted in a socket 23 and is not pivoted upon the face of the pawl 21. In Fig. 5 I also show a means whereby the driving pawl 21 after it is raised out of engagement with the teeth on the wheel 24 may be held out of such engagement and this latching arrangement is entirely adapted to be used in connection with the constructions shown in Figs. 3 and 4.

The crank case 19 is formed with an opening 28 and attached to the pawl 21 is a spring 29 which extends through this opening 28 and is provided with a lip 30. When the pawl 21 is forced outward by the action of the pawl 22, this lip 30 will engage over the margin of the opening 28 and the pawl 21 will be held supported out of engagement with the teeth on wheel 24. This catch, formed by the spring 29, insures against the possibility of the pawl 21 being thrown into engagement while the driven element is still rotating. Of course, the pawl 21 would be immediately thrown out of engagement by the action of the pawl 22, but there would

be unnecessary wear and jar. By using the catch 29, the pawl is held out of engagement when once thrown. The catch may be tripped with the finger, whereupon the pawl 5 21 will return to its usual position.

What I claim is:

1. In a mechanical movement of the character described, a rotatable driving element, a rotatable driven element, the driven 10 element being formed with ratchet teeth, a pawl on the driving element engaging with said ratchet teeth, a spring holding the pawl in engagement with the ratchet teeth, a non-rotatable element mounted concentric 15 to the center of rotation of said driven and driving elements and formed with peripheral ratchet teeth reverse to the ratchet teeth on the driven element, a pawl carried by the first named pawl and acting in a re- 20 verse direction thereto and engaging the teeth of the non-rotatable element, said non-rotatable element being longitudinally shiftable with relation to the driven element.
- 25 2. In a mechanical movement, a rotatable driving element, a rotatable driven element, both moving about a common center, the driven element being formed with ratchet teeth, a pawl carried by the driving element and engaging the teeth of the driven element, a spring holding the pawl in positive engagement with said teeth, a non-rotatable ratcheted member concentric to said common center and having ratchet teeth re-

versely disposed to the ratchet teeth on the 35 driven member, a pawl carried by the first named pawl and extending in a reverse direction thereto, the extremity of said pawl engaging the teeth of the non-rotatable ratcheted member, a casing having an opening, and a resilient detent attached to said first named pawl and projecting into said opening, said detent being formed with a head adapted to engage over the wall of said opening when the first named pawl is 45 forced outward.

3. In a mechanical movement, a driving element, a driven element, means for connecting the driving element with the driven element while the driving element is moving in one direction, means operated by a reverse movement of the driving element for disconnecting said connecting means, a member having an opening disposed opposite to the engaging means for the driving 55 element, and a resilient detent mounted on said connecting means and projecting into said opening, said detent being resilient and having a head on its outer end adapted to engage over the wall of the opening when 60 the connecting means is moved outward.

In testimony whereof, I affix my signature in presence of two witnesses.

FENTON TOMLINSON. [L. s.]
